UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

FUEL-DISTRIBUTER.

1,391,744.

Specification of Letters Patent. Patented Sept. 27, 1921.

Application filed June 19, 1920. Serial No. 390,143.

To all whom it may concern:

Be it known that I, NATHAN M. LOWER, a citizen of the United States, and resident of Pittsburgh, county of Allegheny, and State 5 of Pennsylvania, have invented certain new and useful Improvements in Fuel-Distributors, of which the following is a specification, and which are illustrated in the accompanying drawings, forming a part 10 thereof.

The invention relates to devices used in connection with mechanical stokers for distributing fuel, such as coal, within a fire-box; its object being to provide for the even 15 distribution of the fuel over the grate.

The invention consists of a tubular body having an open end and adapted to be horizontally positioned within the fire-box wall, and being provided with nozzles at its 20 inner end adapted to discharge jets of fluid, such as steam or air, obliquely backward for the purpose of deflecting a portion of the fuel impelled through the tube by any suitable means to spread it upon the grate at 25 the end of the fire-box at which the distributor is located, and especially to insure the deposit of an ample supply of fuel upon the corners of the grate; such nozzles being located at the top or bottom of the tube, or 30 at both of these positions.

In the drawings showing a preferred form of construction—

Figure 1 is a plan view of a distributor;

Fig. 2 is a longitudinal vertical section, 35 partly in elevation; and

Fig. 3 is a rear end view thereof.

The distributor preferably takes the form of a tube 29, having a flat bottom 30 and being adapted to be secured within an opening in the wall of the fire-box, there being 40 shown as a convenient means for such attachment an aperture 31 in the upper portion of the tube adjacent its rear end within which a retaining hook may be engaged.

The tube 29 is open at its inner end to 45 permit the free discharge of fuel impelled therethrough by any preferred means, and in the embodiment shown is also open at its rear end to receive the fuel from any suitable source of supply, such as an elevator or a hopper, though it is immaterial to the present invention whether the receiving opening be at the end or laterally.

At the forward end of the tube 29 there 50 is a forwardly extending flange 32, prefer-

ably formed integral with the body, as shown, the lower face of this flange being given any desired configuration but is preferably flat, as shown. A portion of the fuel which may be impelled through the tube at 60 considerable velocity will strike the under face of the flange 32, and be thereby directed downwardly and scattered over a zone of considerable width.

Depending from the flange 32 is a nozzle 65 33, here shown as in the form of a hollow integral boss, this nozzle being provided with a plurality of discharge openings, as 34, which are directed backwardly and downwardly, and some of them oblique to 70 the direction in which the fuel is advanced through the tube. Fluid under pressure is supplied to the nozzle 33 through a suitable duct 35, which in the disclosed form of construction is cored in the top wall of the tube, 75 there being provided a suitable opening at which a service pipe may be attached. For this latter purpose there is shown such openings at 36, 37, and 38, any or all of 80 which may be used.

A similar nozzle 39 is secured at the forward end of the bottom of the tube. If desired, this nozzle may take the form of an elbow nipple, as shown, screwed into the end of the tube 29 to communicate with a 85 cored duct 40, supplied with fluid under pressure through suitable pipes connected with its rear end, as at 41 or 42. Whatever may be its specific form the nozzle 39 projects upwardly above the floor or bottom 90 of the tube 29, and is provided with a plurality of laterally and backwardly directed openings, as 43, 44, adapted to discharge fluid jets which will deflect portions of the advancing fuel to the corners of the fire- 95 box.

Various embodiments of the invention may be made which will come within its scope, the essential feature of which is the location of the scattering jets at the inner 100 end of a fuel induction passage.

I claim as my invention—

1. In a fuel distributor, an open ended tube adapted to be disposed in a substantially horizontal position and through which 105 fuel may be impelled, and a fluid-discharging nozzle at the upper side of the forward end of the tube and having its outlet ports backwardly and downwardly directed.

2. In a fuel distributor, an open ended 110

2

tube adapted to be disposed in a substantially horizontal position and through which fuel may be impelled, and a fluid discharging nozzle at the upper side of the forward 5 end of the tube and having its outlet ports backwardly, downwardly and laterally directed.

3. A distributer tube having a flat bottom and an open discharge end and adapted to be 10 horizontally positioned and having a flange projecting from the upper portion of its discharge end, a fluid nozzle projecting upward at the forward end of its bottom and discharging obliquely backward, and a fluid 15 nozzle depending from the flange and discharging backwardly.

4. A distributer tube having a flat bottom and an open discharge end and adapted to be horizontally positioned and having a flange 20 projecting from the upper portion of its discharge end, a fluid nozzle projecting upward at the forward end of its bottom and dis-

charging obliquely backward, and a fluid nozzle depending from the flange and discharging obliquely backward. 25

5. A fuel distributer comprising a passage through which fuel may be impelled, and a fluid discharging nozzle located at the inner end of the passage and adjacent its upper portion and having jet openings directed 30 obliquely backward.

6. A fuel distributer comprising a passage through which fuel may be impelled, and a fluid nozzle located beyond the delivery end of the passage and having jet openings directed 35 obliquely backward.

7. A fuel distributer comprising a passage through which fuel may be impelled, and a fluid nozzle located beyond the delivery end of the passage and depending into the line 40 of the path of fuel impelled through such passage and having jet openings directed obliquely backward.

NATHAN M. LOWER.
